UNITED STATES PATENT OFFICE

112,255

DESIGN FOR A DOMESTIC ICE CREAM FREEZER

Harry J. Kettleborough, Mendota, Ill., assignor to
H. D. Conkey & Company, Chicago, Ill., a corporation of Illinois

Application July 7, 1938, Serial No. 78,334

Term of patent 14 years

To all whom it may concern:

Be it known that I, Harry J. Kettleborough, a citizen of the United States and a resident of Mendota, in the county of La Salle and State of Illinois, have invented a new, original, and ornamental Design for a Domestic Ice Cream Freezer, of which the following is a specification, reference being had to the accompanying drawing, forming a part thereof.

Referring to the drawing:

Fig. 1 is a perspective view of an ice cream freezer showing my design; and

Fig. 2 is a perspective view, taken from the opposite side thereof.

I claim:

The ornamental design for a domestic ice cream freezer, as shown.

HARRY J. KETTLEBOROUGH.
